STEAM PRESSURE REGULATOR

Charles M. Terry, Decatur, Ill., assignor to A. W. Cash Company, Decatur, Ill., a corporation of Delaware

Application February 11, 1935, Serial No. 5,991

2 Claims. (Cl. 60—54.5)

This invention relates to steam pressure regulators, and more particularly to regulators of the type having a power actuated motor which is controlled automatically in response to variations in the pressure of steam.

It is known practice in this art to apply the variable steam pressure to a flexible diaphragm, and to utilize the movements of the diaphragm to actuate a pilot mechanism, such as a valve. The 10 pilot mechanism in turn controls a motor, which may be of the hydraulic type. Regulators of this construction are used for controlling stokers, dampers, rheostats, valves, etc., and they function with a high degree of satisfaction so long as 15 the steam pressure is not excessive. However, many plants today are utilizing steam at pressures of 500 lbs. per square inch or over. At such high pressures, the diaphragm has to be made very thick in order to avoid rupture, and as a result it lacks the degree of flexibility necessary for 20 response to slight changes in steam pressure.

It is accordingly the main object of the present invention to overcome these difficulties and to provide a steam pressure regulator which can be 25 used with steam at very high pressures, and which will respond to the slightest change in the pressure of the steam.

It is a further object of the invention to provide a steam pressure regulator suitable for use with 30 high pressures and so constructed and arranged that the pressure responsive element can move with substantially no friction and wear.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts, the single figure is an elevation, partly in section, of a steam pressure regulator arranged to operate a balanced valve in a steam main.

The embodiment illustrated comprises a regulator 10 arranged to control the pressure in a steam main or pipe line 11 by means of a balanced valve 12 in the line. This valve is of the ordinary double-disk type well known in the art. Steam flows through the pipe in the direction of the 50 arrow.

The regulator 10 comprises a cylinder 14 and a piston 15 slidable therein forming a hydraulic motor. A piston rod 16 extends upwardly from the piston 15 and through a stuffing box 18 at the 55 upper end of the cylinder. The piston rod is con-

nected by a link 19 to one end of a lever 20. The opposite end of the lever is pivoted to the stem 22 of the balanced valve 12, and the lever is supported intermediate its ends by a link 23 mounted on the valve casing. 5

The piston 15 is actuated by fluid pressure under the control of a pilot valve mechanism 25 of the four-way type connected to the ends of the cylinder 14 by means of tubes 26. A suitable fluid, such as oil, is delivered under pressure to the 10 valve mechanism 25 through a tube 27, and exhaust fluid is removed through a pipe 28. The valve mechanism 25 is provided with an upwardly projecting reciprocable valve stem 29. For a more detailed description of the four-way valve 15 mechanism reference may be had to the patent to Paul C. Temple No. 1,890,472, granted December 13, 1932.

In order to actuate the pilot valve, I provide a horizontal arm or lever 31 fulcrumed at one end 20 on a downwardly extending knife-edge 32. This arm 31 is connected by a vertical rod 33 to one end of a horizontal lever 35, the other end of which is connected to the valve stem 29. The lever 35 is fulcrumed on the upper end of a vertical rod 36, the lower end of the rod being connected to one end of a horizontal lever 37 fulcrumed at 39. The other end of the lever 37 is connected by a vertical link 40 to a horizontal projection 41 forming part of a member 43. This 30 member 43 is fulcrumed at 44 and slidably supports an inclined rod 45 having its upper end pivotally connected to the piston rod 16. With this construction the piston 15 will assume predetermined positions in its stroke corresponding to the 35 positions imparted to the arm 31.

In order to obtain the desired automatic operation, means is provided to place the arm 31 in definite positions corresponding to changes in the steam pressure in the main 11 within a predetermined range. For this purpose I provide a piston 47 having a comparatively small diameter, which is slidable vertically in a cylinder or guide-way 48. This piston is elongated and formed with a deep central recess or pocket 49 extending 45 downwardly from the top of the piston nearly to the bottom thereof. A vertical strut or rod 51 fits loosely within the recess 49 with its lower end in contact with the bottom wall of the recess. This strut 51 carries at its upper end a knife-edge 50 52 which engages the lower surface of the arm 31 at a point slightly offset laterally from the knife-edge 32. The pressure in the main 11 is applied to the lower surface of the piston 47 by means which will be described hereinafter, and 55

this causes an upward thrust on the strut 51 and knife-edge 52, tending to lift the arm 31. In order to resist the movement of the arm, weights 53 and 54 are attached to the outer end thereof. 5 Since the area of the piston 47 does not vary, I preferably connect a spring 56 to the arm 31, so that the loading of the arm will vary slightly throughout its operative range and an appreciable variation in steam pressure will be required to 10 cause complete travel of the arm between its limit stops 57. The spring 56 is of the coiled tension type, supported at its lower end by a bracket 58. The force of the spring may be adjusted by means of a wing nut 59. It will be apparent that the 15 weights and spring serve to bias the piston 47 in a downward direction.

In steam pressure regulators as heretofore constructed the steam pressure has been applied to the pressure responsive element through a body 20 of water formed by the condensing of the steam. While this is satisfactory for diaphragm-type regulators, it has serious disadvantages when a piston is utilized as the pressure responsive device. It is not advisable to use piston rings or 25 other forms of packing to prevent leakage past the piston, for this will cause excessive friction and greatly reduce the sensitivity of the regulator, and yet if no packing is provided the water will leak past very rapidly, particularly at the 30 high pressures with which the present invention is concerned. Such leakage will cause corrosion and excessive wear, which in turn will increase the rate of leakage. This leakage of condensate also represents a thermal loss, and will require 35 special means for disposal thereof.

In order to avoid these difficulties I preferably utilize a piston 47 without piston rings or other friction producing packing devices. The piston may be formed with a series of spaced circumferential grooves 61 which are of value in decreasing both the leakage and the sliding friction. At the bottom of the cylinder 48 I attach a reservoir 62, and the bottom of this reservoir is connected to the steam main 11 by means of a pipe 40 or conduit 63 provided with a valve 64. At installation this pipe 63 is filled with water, or it is allowed to fill with condensate from the steam, the pipe being looped downwardly in the form of a U or otherwise shaped to retain water, and the reservoir 62 is filled with oil. This oil is 45 preferably a heavy mineral oil, an oil of the grade known as 600-W having been found satisfactory for the purpose. This oil floats on the water in the pipe 63 and transmits the pressure 50 to the piston 47. Because of the comparatively high viscosity of the oil, it leaks past the piston at a very slow rate. At the same time it lubricates the piston, prevents corrosion, and increases the sensitivity of the regulator.

60 In order to prevent any grit or other foreign matter from entering the cylinder 48, I preferably provide a flexible diaphragm 66 over the top of the cylinder. The central portion of the diaphragm is secured to the strut 51, and its 65 peripheral portion is clamped against the regulator frame by means of an annular flange 67 at the upper end of the cylinder 48. This diaphragm serves as a lateral support for the strut 51, as well as a dirt excluding device. Since the diaphragm is not under pressure, it can be made very 70 flexible.

While the leakage of oil past the piston is very small, I prefer to provide means for collecting the oil and returning it to the reservoir 62. 75 For this purpose there is shown a receptacle 69

located at one side of the cylinder 48. This receptacle is provided with a sight glass 70 and a removable cover plate 71 having a vent 72 therethrough. A tube 74 connects the receptacle 69 with the space below the diaphragm 66, the bottom of the receptacle being connected to the reservoir 62 by means of a pipe 75 provided with a valve 76. A drain pipe 78 is connected to the reservoir near the bottom thereof, and this pipe is provided with a valve 79.

10 The operation of the invention will now be apparent from the above disclosure. Under normal conditions the piston 15 will remain stationary, with the valve 12 partially open. The steam pressure in the main 11 will be transmitted through 15 the pipe 63 to the oil in the reservoir 62, and through the oil to the piston 47 and the knife edge 52. This will support the arm 31 in equilibrium against the loading of the weights 53 and 54 and the spring 56. The pilot valve mechanism 25 20 will be in neutral position. If the steam pressure in the main increases slightly, the arm 31 will move upwardly to a new position, at the same time acting through the rod 33 and lever 35 to lower the valve stem 29 and admit fluid to the 25 upper end of the cylinder 14, while exhausting fluid from the lower end. The piston 15 will move downwardly, and the rod 45 will swing the member 43, which will actuate the rod 40, lever 37, rod 36, and lever 35, raising the valve stem 29. 30 As soon as the pilot valve mechanism 25 reaches neutral position, the piston 15 will stop. The movement of the piston 15 will have slightly closed the valve 12 to counteract the rising steam pressure. In a similar manner, a decrease in 35 steam pressure will cause movement of the parts in the reverse direction.

The regulator can be constructed for very high steam pressures, and since no packing is required for the piston 47 it will respond to the 40 slightest change in pressure. The lubricating effect of the oil contributes to this sensitive operation. Because of the comparatively high viscosity of the oil, leakage past the piston 47 will be very slight, and such oil as does leak by will 45 escape through the tube 74 to the receptacle 69. When the operator notes from the sight glass 70 that considerable oil has accumulated, he will close the valve 64 and open valves 76 and 79. The oil which has escaped past the piston will 50 have been replaced by water in the lower part of the reservoir 62, and this water will now flow out through the pipe 78, allowing the oil from the receptacle 69 to return by gravity to the reservoir 55 through the pipe 75. As soon as oil appears at the discharge of the pipe 78, the operator will close the valves 79 and 76, and open the valve 64, thus placing the oil under pressure again. Whenever necessary, additional oil can easily be 60 introduced into the system by removing the cover plate 71 and pouring the oil into the receptacle 69.

Having thus described my invention, what I claim as new and desire to secure by Letters Pat- 65 ent is:

1. A control mechanism for a steam pressure regulator comprising a cylinder, a piston slidable in the cylinder, loading means biasing the piston in one direction, a reservoir connected at its 70 upper end to the cylinder, a body of oil in the reservoir and in contact with the piston, and a U-shaped steam pressure conduit connected to the lower end of the reservoir, the steam pressure conduit serving to retain a confined body 75

of water beneath the oil and in direct contact therewith.

2. A control mechanism for a steam pressure regulator comprising a vertical cylinder, a piston slidable in the cylinder, loading means biasing the piston downwardly, a reservoir beneath the cylinder, the upper end of the reservoir being connected to the lower end of the cylinder, a body of

oil in the reservoir and in contact with the piston, and a U-shaped steam pressure conduit connected to the lower end of the reservoir, the steam pressure conduit serving to retain a confined body of water beneath the oil and in direct contact therewith. 5
